CLAIM

The ornamental design for a mounting plate for an exercise machine, as shown and described.

DESCRIPTION

FIG. 1 is a front perspective view of a mounting plate for an exercise machine, showing my new design, the associated exercise machine structure being shown in broken line;

FIG. 2 is an expanded perspective view thereof;

FIG. 3 is a front elevation view thereof, the rear view being a mirror image thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines are shown for illustrative purposes only and form no part of the claimed design.
